(57) **CLAIM**

The ornamental design for a water resistant pouch, as shown and described.

DESCRIPTION

FIG. 1 illustrates a front perspective view of the new design for a water resistant pouch;

FIG. 2 illustrates a rear perspective view thereof;

FIG. 3 illustrates a front view thereof;

FIG. 4 illustrates a rear view thereof;

FIG. 5 illustrates a right side view thereof;

FIG. 6 illustrates a left side view thereof;

FIG. 7 illustrates a top view thereof;

FIG. 8 illustrates a bottom view thereof; and,

FIG. 9 illustrates a front view thereof wherein the top of the pouch is open.
The broken lines in the drawings illustrate portions of the water resistant pouch which form no part of the claimed design.
